APPARATUS FOR INTRODUCING FLUID
INTO A DEEP WELL PUMP.Clarence J. Coberly, Los Angeles, Calif., assignor
to Roko Corporation, Reno, Nev., a corpora-
tion of Nevada

Application April 21, 1937, Serial No. 138,177

19 Claims. (Cl. 103—203)

My invention relates to the deep well pumping art, and more particularly to an apparatus for introducing a fluid to be pumped into a deep well pump.

Although my invention is susceptible of many uses, it is of particular utility in the oil industry and will be described in connection with a deep well pump adapted to pump oil from an oil well. It is to be understood, however, that this application of the invention is for the purpose of illustration only, and I do not intend to be limited thereby to the specific use described.

In the pumping of oil wells numerous types of pumps may be successfully utilized, as is well known in the art. Although the type of pump utilized forms no part of my present invention, I prefer to use my invention in conjunction with a fluid operated deep well pump of the type disclosed in my copending Patent No. 2,081,223, issued May 25, 1937, entitled "Fluid operated deep well pump", which discloses a pump and motor unit adapted to be positioned in a well so as to pump fluid therefrom.

As is well known in the art, oil to be pumped from a well frequently has a substantial quantity of gas mixed therewith or in solution therein. The amount of gas in solution under equilibrium conditions depends on the temperature and pressure in the well and the analysis of both the oil and the gas. It is possible for the oil to be supersaturated, i. e., to have more gas in solution than the amount normally corresponding to equilibrium conditions. When the pressure on the well fluid is decreased, the temperature increased, or when the fluid is agitated, relatively large quantities of the gas therein are frequently liberated and separate from the oil and form a foam or an emulsion therewith. Such gas produces a number of detrimental effects in the pumping, treating, conveying, and storing of the pumped fluid, and numerous devices have been devised and are common in the art for separating such gas from the oil. Prior art devices for separating the gas from the oil prior to the pumping of the oil from the well have not produced satisfactory results, and it is a primary object of my invention to provide an apparatus for separating at least a portion of the gas in the fluid to be pumped from a well therefrom prior to pumping such fluid from the well.

It is another object of my invention to provide an apparatus for introducing into a pump a liquid normally having a high degree of gas

saturation, in which the degree of gas saturation is reduced before the liquid enters the pump.

Another object of my invention is to supply an apparatus for introducing into a pump a liquid normally supersaturated with gas, in which the 5 degree of supersaturation of the liquid is reduced, and the degree of saturation is then further reduced before the liquid enters the pump. I prefer to accomplish this by reducing the pressure on the liquid to decrease the degree of supersaturation thereof and then increasing the pressure thereon to reduce the degree of saturation.

Another object of my invention is to provide an apparatus for use in connection with a deep 15 well pump of the character described above for reducing to a minimum the tendency of the pump to cause the release of gas from the pumped fluid and the resulting loss of pump capacity due to the space occupied by such gas. 20

A still further object of the invention is to provide an apparatus for separating gas from a fluid to be pumped by creating a sudden drop in pressure between spaced portions of the fluid before the fluid enters the pumping means 25 adapted to pump said fluid.

Another object of my invention is to provide an apparatus for separating gas from a fluid to be pumped by passing said fluid through an orifice designed so as to decrease the fluid pressure on said fluid. 30

Still another object of my invention is to provide means for separating gas from a fluid to be pumped by passing said fluid through an orifice and maintaining a substantially uniform 35 pressure differential across the orifice.

A further object of the invention lies in providing an apparatus for separating gas from a fluid to be pumped by maintaining a substantially uniform pressure differential between 40 spaced portions of a fluid to be pumped regardless of fluctuations in the amount of fluid pumped.

Another object of the invention is to provide agitation of a fluid to be pumped before it enters the pump by subjecting the fluid to a turbulent 45 flow through an orifice.

Another object of my invention is to provide an apparatus for separating gas from a fluid to be pumped by passing the fluid through an orifice, and returning the separated gas to a column of fluid on the outside of the orifice. 50

Other objects and advantages of the invention will appear from the following specification and drawing, which is for the purpose of illustration only and in which:

Fig. 1 is a sectional view of the inlet member of my invention installed in conjunction with a deep well pump.

Fig. 2 is a sectional view of an alternative form of my invention.

Fig. 3 is an enlarged sectional view of still another alternative form of my invention.

Fig. 4 is an enlarged detail view of the inlet valve of Fig. 3.

10 Referring to the drawing, Fig. 1 shows an inlet member 10 threaded at 11 to a collar 12 which in turn is threaded secured to an oil well tubing 13. The oil well tubing 13 may be suspended in a well by any suitable means well known in the 15 art, such as a casing head or other means, not shown. The collar 12 is internally threaded to receive the upper end of a tube 16 forming a pump receptacle member which is concentric with and projects downwardly in the inlet member 10. The tube 16 is internally threaded at its lower end 17 to receive a valve body 18 having a chamber 19 in the lower part thereof which is connected to the interior of the pump receptacle 16 by a vertical passage 20, the upper end 25 of which is flared to form a pump seat 21. A radial opening 22 in the wall of the valve body 18 connects the chamber 19 with the exterior of the valve body, and has therein a valve seat 23 adapted to be engaged by a closure member 24 30 preferably consisting of a metal ball disposed in the chamber 19.

A deep well pump mechanism 28, which may be of any desired type but which is preferably of the type disclosed in my copending Patent No. 3,208,122, is provided at the lower end with a tapered portion 29 adapted to seat in the pump seat 21 and to form a fluid-tight seal between the pump and the valve body 18. The pump 28 may be lowered through the oil tubing 13 or 40 otherwise positioned therein so as to seat on the pump seat 21, so as to be capable of drawing fluid thereinto from the passage 20 and pump it upwardly through the tube 16 and the oil tubing 13.

The inlet member 10 has an auxiliary valve member 30 internally threaded at 31 to the collar 12, the valve member having an internally threaded recessed portion 31a at its lower end. The valve member 30 is provided with a passage 32 therein which communicates between the interior of the inlet member 10 and the exterior thereof, and directly communicates with a space 25 between the inlet member and the tube 16, the passage 32 being counterbored at 33 to provide a seat for a closure member preferably 55 formed by a metal ball 34, the passage and the ball forming auxiliary valve means for releasing gas from the interior of the inlet member as hereinafter described. A ring member 35 is threaded on the upper end of the valve member 60 30 and partially obstructs the outer end of the counterbore 33 so as to permit gas to pass through the passage 32 from the interior to the exterior of the inlet member 10 but confining the ball 34 in the counterbore, the ball being free to move 65 therein so as to permit the passage of such gas. Threadedly secured to the lower end of the valve member 30 is an upper tube member 38 on the lower end of which is threadedly received an inlet collar 39 having fluid orifices 40 therein 70 which may be of any convenient form which will create a pressure differential thereon when fluid is flowing therethrough as described hereinafter. I prefer to provide six orifices 40 spaced around the perimeter of the inlet collar 39 and communicating between the exterior thereof and the

space 25 between the inlet member 10 and the tube 16, although any desired number of orifices may be used without departing from the spirit of the invention. I also prefer to form the orifices 40, as shown in Fig. 1, so that they 5 slant upwardly and inwardly from their external openings 41 on the exterior of the inlet collar to their internal openings 41 on the interior of the collar, so that the fluid is directed upwardly toward the upper end of the space 25. Internally 10 threaded in the lower end of the inlet collar 39 is a lower tube member 43, which is preferably of the same diameter as the upper tube 38, to the lower end of which a closure member 44 is connected by a threaded lower collar 45. In 15 practice, the tubes 38 and 43 may be made in one or more sections threaded together by suitable collars to obtain correct lengths of the upper and lower portions of the space 25. Although I have shown the upper sleeve 38, the inlet collar 20 39, the lower sleeve 43, the lower collar 45, and the closure member 44 as separate elements for simplicity of manufacture, it will be understood that these elements can be formed integrally as a single shell without departing from the spirit 25 of the invention. The closure member 44 forms a chamber 46 surrounding and extending below the inlet body 18 and communicating with the space 25.

In practice, the inlet member 10 is secured to 30 the pump tubing 13 by the collar 12, and the tubing is lowered into the well until the inlet member is wholly submerged in the fluid in the well which is to be pumped. The level of fluid in the well is diagrammatically represented in 35 Fig. 1 by the line A—A, but it will be understood that ordinarily in practice this level may be considerably higher relative to the inlet member 10. Before actuation of the pump 28 is commenced, the head of fluid in the well forces well fluid 40 through the orifices 40 into the chamber 46 and the space 25. The well fluid substantially fills the space 25 so as to form a column of fluid in the space above the orifices 40, although a small amount of gas may remain in or collect in the 45 upper end of the space.

In operation, when the pump 28 is started, well fluid is drawn through the opening 22 and the valve seat 23, the ball 24 moving away from the seat to permit such entry of fluid. As fluid is 50 pumped out of the chamber 46 by the pump 28, fluid pressure in the space 25 is reduced, and the head of fluid in the well above the orifices 40 operates to force well fluid through the orifices into the interior of the inlet member 10. The 55 orifices 40 are restricted openings so that any flow of well fluid therethrough creates a substantial pressure differential on the orifices. It will be apparent that the pressure of the well fluid at the opening 41 at the outer end of the 60 orifice 40 will always be considerably higher than the pressure of the fluid at the opening 42 at the inner end of the orifice when the pump 28 is being actuated. This drop in pressure is due to the friction loss through the passage 40 and 65 the conversion of pressure head into velocity head in the orifice.

In the form of my invention shown in Fig. 1, the size and shape of the orifices are so designed that for a given flow of fluid through the orifices 70 40, the total drop in pressure thereacross will be equal to the pressure exerted by a head of fluid h_2 such as, for example, between the lines B—B and C—C. It will be understood that the head of fluid in the well between the lines B—B 75

and D—D will not all be required to force the well fluid through the orifices, and that a part thereof comprising a head of fluid h_3 will be available to create an upward pressure in the space 5 above the inner opening 42 of the orifice 40, which I utilize to exhaust gas from the space 25 as described hereinafter, this being an important feature of the invention.

As pointed out, the well fluid flowing into the 10 openings 41 of the orifices 40 may be mixed with gas as well as supersaturated with gas, but due to the reduction of pressure in the orifices 40, as the fluid flows inwardly therethrough a substantial part of this gas is freed from the fluid by 15 this drop in pressure therein and by the turbulence caused by the discharge of this fluid into the space 25, and when the fluid and free gas expand by reduction of pressure into the space 25, the gas rises through the fluid therein to the 20 top of the space where it collects. The head h_1 , which is the amount the fluid level is depressed below the line C—C, exerts an upward force against the gas collected in the upper end of the space 25, and this gas in turn exerts an upward 25 force against the ball 34. Consequently, the upward force exerted on the ball 34 is equal to the head h_4 plus the head h_1 , whereas the downward force is merely equal to h_1 , and, accordingly, the ball moves away from its seat to permit excess 30 gas in the space 25 to exhaust through the passage 32 and the counterbore 33 into the well. It will be understood that the pressure exerted by the head h_4 on the ball 34 depends upon the amount of gas in the upper end of the space 25, 35 due to the difference in specific gravities of the gas and the oil. Thus, if the space 25 is entirely filled with oil, the effective upward pressure tending to move the ball 34 will be zero, but as the amount of gas in the space increases beyond h_2 , the effective upward pressure h_4 approaches the head h_3 . As soon as sufficient gas has exhausted from the space 25 to reduce the pressure in the space below the pressure exerted by the head h_1 and the weight of the ball 34, the ball seats to 40 close the auxiliary valve means. In operation, the internal and external pressures on the ball 34 quickly attain a substantial balance at which the level of oil in the space 25 maintains a substantially uniform level such as represented by 45 the line E—E. As additional gas collects in the upper end of the space 25, the pressure therein increases, and the ball 34 is unseated to permit such gas to exhaust into the well, the level E—E of the fluid in the space 25 remaining substantially constant.

It will also be noted that the inlet orifices 40 are positioned considerably above the radial opening 22 of the inlet body 18 to provide a fluid head h_5 between the lines D—D and F—F. The 50 elements of the device are so formed and positioned that the pressure exerted by the head h_5 is always greater than the friction head required to draw the pumped fluid into the pump 28 at the normal pumping capacity so that the fluid is 55 always less than saturated with gas when it passes into the pump. This feature of construction is important in that it provides an additional means for lowering the gas saturation of the pumped fluid prior to pumping, which prevents the liberation of gas in the pump during pumping and insures that the pump is entirely filled with oil and free from gas bubbles.

An alternative embodiment of the invention is 70 shown in Fig. 2, in which an inlet member 50 is connected to a collar 51 of oil well tubing 52

through an annular valve member 53 having a valve passage 54 containing a closure element 55. In this embodiment a pump receptacle tube 56 is threaded directly to the collar 51, the valve member 53 making a sliding fit with the exterior 5 of the tube and being in engagement with a shoulder 57 formed on the collar. The valve member 53 is provided with an external shoulder receiving an upper sleeve 58 of the inlet member 50 which bears against an upper shoulder of an 10 inlet collar 59 which in turn has a lower shoulder which bears against a lower sleeve 60. The inlet collar 59 is provided with inlet orifices 61 similar in function to the orifices 40 shown in Fig. 1, but has one or more studs 62 adapted to engage the 15 pump receptacle 56 to concentrically align the upper and lower sleeves 58 and 60 therewith. The lower end of the lower sleeve 60 bears against a shoulder formed on a closure member 63.

The pump receptacle tube 56 is provided at its 20 lower end with a valve body 64, similar in construction and function to the valve body 18 shown in Fig. 1, but having a threaded opening 65 in the lower end thereof adapted to receive a threaded bolt 66 projecting through an axial opening 67 25 in the closure member 63. The lower end of the bolt 66 is provided with a nut 68, and when the elements of the inlet member 50 are assembled as shown in Fig. 2, the nut may be tightened to draw the closure member 63 upwardly relative to the 30 pump receptacle 56 to form fluid-tight joints between all the elements. Thus, when the device is assembled, fluid-tight fits are formed between the valve member 53 and the shoulder 57, between the valve member 53 and the upper sleeve 35 58, between the upper sleeve 58 and the inlet collar 59, between the inlet collar 59 and the lower sleeve 60, and between the lower sleeve 60 and the closure member 63. The operation of the device shown in Fig. 2 is the same as the 40 operation of the embodiment shown in Fig. 1, as described hereinabove, excess gas being discharged through the gas valve formed by the valve passage 54 and closure element 55. The chief advantage of the construction shown in 45 Fig. 2 is its simplicity of elements and ease of assembly.

Another alternative embodiment is shown in Fig. 3, which has the same general construction as the form shown in Fig. 2. A collar 70 is engaged by an annular valve member 71, similar to the valve member 53, which is in turn engaged by an outer sleeve 72. The outer sleeve 72 is provided with studs 73 adapted to axially align the sleeve with a pump receptacle 74, similar to the 55 pump receptacle 56. The sleeve 72 has an external annular channel 75 covered by a tubular screen 76 suitably fixed to the sleeve, and has an inlet passage 77 formed therein communicating between the annular channel and a passage 78 60 in an annular ring 79 formed integrally with the sleeve 72 or suitably fixed therein as by welding. The passage has a lower enlarged counterbore portion 80 which receives a ball valve member 81 held in seating engagement with the upper end 65 of the counterbore by a compression spring 82. A threaded plug 83 closes the lower end of the counterbore and has an opening 84 therein to permit the passage of fluid therethrough. The pump receptacle 74 has an inlet body 85 at its 70 lower end, similar in construction to the inlet body 64.

In operation, the spring-actuated inlet valve, formed by the valve member 81 and the spring 82, maintains a uniform pressure differential across 75

the inlet passages 77 and 78 regardless of the length and size of the passages, whereas in the embodiments shown in Figs. 1 and 2 the length and size of the inlet orifices have to be very carefully coordinated to maintain the correct desired stabilizing action on the fluid flowing therethrough. This is an important feature of this embodiment of the invention. Furthermore, with the construction shown in Fig. 3, a variable amount of fluid can flow through the inlet passages 77 and 78 without varying the pressure drop therein, due to the uniform action of the compression spring 82, and consequently the agitation of the fluid flowing through the passage 15 remains uniform regardless of the amount of fluid flowing therethrough. The screen 16 acts to prevent clogging of the inlet passages 77 and 78. Although I have only shown one inlet valve in the annular ring 19, I prefer to use three of such 20 valves spaced at equal intervals around the shoulder, and it will be apparent that any desirable number may be used depending upon pumping conditions.

I claim as my invention:

25 1. In a deep well pumping device, the combination of: pump means adapted to pump fluid from a well, said pump means having a pump inlet; an inlet member connected to said pump means so as to supply well fluid thereto, said inlet member having an orifice communicating be-

30 tween said well and the interior of said member at a point above said pump inlet, said orifice being so formed that a pressure differential is impressed on well fluid flowing therethrough so as to separate gas from said fluid, said gas collecting in said member; and valve means associated with said member for removing at least a portion of said gas from said member.

35 2. In a deep well pumping device, the combination of: pump means adapted to pump fluid from a well, said pump means having an inlet; walls forming a chamber communicating with said inlet; means for conducting well fluid into said chamber at a point above said inlet, said means being adapted to reduce the pressure on said fluid flowing into said chamber below the fluid pressure in said well so as to cause gas to separate from said fluid and collect in said chamber; valve means for permitting the escape of gas from said 40 chamber; and means for maintaining the amount of gas in said chamber below a predetermined maximum.

45 3. In a deep well pumping device, the combination of: pumping means adapted to be positioned in a well adjacent the production zone thereof; a shell member forming a chamber; means for securing said shell member relative to said pumping means; walls forming a restricted orifice communicating between the fluid in said well and said chamber, said orifice being so formed as to impress a substantial pressure differential on fluid flowing therethrough so as to separate gas therefrom in said chamber; fluid inlet means communicating between said chamber and said pumping means, said inlet means being below said orifice; and valve means associated with said walls for permitting at least a portion of said gas to escape from said chamber.

50 4. In a deep well pumping device, the combination of: pumping means adapted to be positioned in a well adjacent the production zone thereof; a shell member forming a chamber; means for securing said shell member relative to said pumping means; walls forming an orifice 55 communicating between the fluid in said well and

said chamber, said orifice being so formed as to impress a pressure differential on fluid flowing therethrough so as to separate gas therefrom in said chamber; fluid inlet means communicating between said chamber below said orifice and said pumping means; valve means associated with said shell member for permitting at least a portion of said gas to escape from said chamber; and means for maintaining the lower level of said gas in said chamber above said orifice. 10

5 5. In a deep well pumping device, the combination of: pumping means adapted to be positioned in a well adjacent the production zone thereof; a shell member forming a chamber; means for securing said shell member relative to said pumping means; walls forming an orifice communicating between the fluid in said well and said chamber, said orifice being so formed as to impress a pressure differential on fluid flowing therethrough so as to separate gas therefrom to 15 collect in said chamber; fluid inlet means communicating between said chamber below said orifice and said pumping means; valve means associated with said shell member above said orifice for permitting at least a portion of said gas to 20 escape from said chamber; and means for maintaining the lower level of said gas in said chamber above said orifice.

6 6. In a deep well pumping device, the combination of: a production tube adapted to be extended down into a well to the fluid producing zone thereof for carrying well fluid to the surface of the ground; an outer shell extending downwardly from the lower end of said tube; a pump receptacle in the lower part of said shell; means connecting the upper end of said pump receptacle to said tube; pumping means adapted to be lowered through said tube into said pump receptacle; means forming a seal between the exterior of said pumping means and said receptacle; an inlet body 40 at the lower end of said receptacle connecting the inlet of said pumping means with the interior of said shell; means for conducting said fluid into said shell from the well above the lower end of said inlet body, said means being so formed 45 as to impress a fluid pressure differential on the fluid flowing therethrough so as to liberate gas in the interior of said shell; and valve means associated with said shell and communicating between the interior of said shell and the well for 50 permitting the escape of at least a portion of said gas from said shell.

7 7. In a deep well pumping device, the combination of: a production tube adapted to be extended down into a well to the fluid producing 55 zone thereof for carrying well fluid to the surface of the ground; an outer shell extending downwardly from the lower end of said tube; a pump receptacle in the lower part of said shell; means connecting the upper end of said pump receptacle to said tube; pumping means adapted to be lowered through said tube into said pump receptacle; means forming a seal between the exterior of said pumping means and said receptacle; an inlet body at the lower end of said receptacle 60 connecting the inlet of said pumping means with the interior of said shell; means for conducting said fluid into said shell from the well, said means being so formed as to impress a fluid pressure differential on the fluid flowing therethrough so as to liberate gas in the interior of said shell; valve means communicating between the interior of said shell and the well for permitting the escape of at least a portion of said gas from said shell; and means between said valve body and said shell for 75

rigidly holding said shell relative to said lower end of said tube and forming a fluid-tight joint therebetween.

8. In a deep well pumping device, the combination of: pump means adapted to pump fluid from a well; an inlet member connected to said pump means so as to supply well fluid thereto, said inlet member having an orifice communicating between said well and the interior of said member, said orifice being so formed that a pressure differential is impressed on well fluid flowing therethrough so as to separate gas from said fluid; and means associated with said orifice for maintaining said pressure differential substantially uniform regardless of fluctuations in the amount of fluid flowing therethrough.

9. In a deep well pumping device, the combination of: pumping means adapted to be positioned in a well; a shell member forming a chamber; means for securing said shell member relative to said pumping means; walls forming an orifice communicating between the exterior of said shell and said chamber, said orifice being so formed as to impress a substantial pressure differential on fluid flowing therethrough so as to separate gas therefrom in said chamber; fluid inlet means communicating between said chamber and said pumping means; valve means for permitting at least a portion of said gas to escape from said chamber; and means associated with said orifice for maintaining said pressure differential substantially uniform regardless of fluctuations in the amount of fluid flowing therethrough.

10. In a deep well pumping device, the combination of: pumping means adapted to be positioned in a well; a shell member forming a chamber; means for securing said shell member relative to said pumping means; walls forming an orifice communicating between the exterior of said shell and said chamber, said orifice being so formed as to impress a substantial pressure differential on fluid flowing therethrough so as to separate gas therefrom in said chamber; fluid inlet means communicating between said chamber and said pumping means; valve means associated with said shell for permitting at least a portion of said gas to escape from said chamber; and means associated with said orifice for maintaining said pressure differential substantially uniform regardless of fluctuations in the amount of fluid flowing therethrough.

11. In a deep well pumping device, the combination of: pumping means adapted to be positioned in a well; a shell member forming a chamber; means for securing said shell member relative to said pumping means; walls forming an orifice communicating between the exterior of said shell and said chamber, said orifice being so formed as to impress a substantial pressure differential on fluid flowing therethrough so as to separate gas therefrom in said chamber; fluid inlet means communicating between said chamber and said pumping means; valve means associated with said shell for permitting at least a portion of said gas to escape from said chamber; and valve means associated with said orifice for maintaining said pressure differential substantially uniform regardless of fluctuations in the amount of fluid flowing therethrough.

12. In a deep well pumping device, the combination of: pumping means adapted to pump fluid from a well; a shell member forming a chamber, said shell member being submerged in the fluid in said well; means for securing said shell member relative to said pumping means; walls form-

ing an orifice communicating between the fluid in said well and said chamber, said orifice being so formed as to impress a pressure differential on fluid flowing therethrough so as to separate gas therefrom in said chamber; fluid inlet means communicating between said chamber and said pumping means at a point below said orifice; and valve means for permitting gas to escape from said chamber, said gas being expelled from said chamber by the action of at least a portion of the submergence head of said fluid above said orifice.

13. In a deep well pumping device, the combination of: pumping means adapted to pump fluid from a well; a shell member forming a chamber, said shell member being submerged in the fluid in said well; means for securing said shell member relative to said pumping means; walls forming an orifice communicating between the fluid in said well and said chamber, said orifice being so formed as to impress a pressure differential on fluid flowing therethrough so as to separate gas therefrom in said chamber, said orifice being so formed that a portion of the submergence head of the fluid in the well above said orifice exerts an upward pressure on the gas in said chamber; fluid inlet means communicating between said chamber and said pumping means; and valve means for permitting gas to escape from said chamber.

14. In a deep well pumping device, the combination of: collar means; an upper tube member secured relative to said collar; an orifice collar connected to the lower end of said upper tube member, having a restricted orifice therein; a lower tube member secured to the lower end of said orifice collar and having its lower end closed, said upper and lower tube members forming a chamber; and a tubular pump receptacle within said chamber adapted to receive pumping means, the lower end of said pump receptacle communicating with said chamber so as to provide an inlet for said pumping means.

15. In a deep well pumping device, the combination of: collar means; an upper tube member secured relative to said collar; an orifice collar connected to the lower end of said upper tube member, having a restricted orifice therein; a lower tube member secured to the lower end of said orifice collar and having its lower end closed, said upper and lower tube members forming a chamber; a tubular pump receptacle within said chamber adapted to receive pumping means, the lower end of said pump receptacle communicating with said chamber so as to provide an inlet for said pumping means; and a valve at the upper end of said upper tube member communicating between said chamber and the exterior of said upper tube member.

16. In a deep well pumping device, the combination of: collar means; an upper tube member secured relative to said collar; an orifice collar connected to the lower end of said upper tube member, having a restricted orifice disposed so as to slant inwardly and upwardly therein; a lower tube member secured to the lower end of said orifice collar and having its lower end closed, said upper and lower tube members forming a chamber; a tubular pump receptacle within said chamber adapted to receive pumping means, the lower end of said pump receptacle communicating with said chamber so as to provide an inlet for said pumping means; and a valve at the upper end of said upper tube member communic-

cating between said chamber and the exterior of said upper tube member.

17. In a deep well pumping device, the combination of: collar means; an upper tube member secured relative to said collar; an orifice collar connected to the lower end of said upper tube member, having a restricted orifice therein; inwardly opening valve means in said orifice; a lower tube member secured to the lower end of said orifice collar and having its lower end closed, said upper and lower tube members forming a chamber; a tubular pump receptacle within said chamber adapted to receive pumping means, the lower end of said pump receptacle communicating with said chamber so as to provide an inlet for said pumping means; and a valve at the upper end of said upper tube member communicating between said chamber and the exterior of said upper tube member.

18. In a deep well pumping device, the combination of: collar means; an upper tube member secured relative to said collar; an orifice collar connected to the lower end of said upper tube member, having a restricted orifice therein; a lower tube member secured to the lower end of said orifice collar and having its lower end closed, said upper and lower tube members forming a chamber; a tubular pump receptacle within said chamber adapted to receive pumping

means, the lower end of said pump receptacle communicating with said chamber so as to provide an inlet for said pumping means; a valve at the upper end of said upper tube member communicating between said chamber and the exterior of said upper tube member; and a perforated tubular member surrounding and spaced from said orifice collar.

19. In a deep well pumping device, the combination of: pumping means adapted to pump fluid from a well; a shell member forming a chamber, said shell member being at least partially submerged in the fluid in said well; means for securing said shell member relative to said pumping means; walls forming an orifice communicating between the fluid in said well and said chamber, said orifice being so formed as to impress a pressure differential on fluid flowing therethrough so as to separate gas therefrom in said chamber, said orifice being so formed that the pressure differential impressed on said orifice is less than the pressure exerted by the submergence head of the fluid in the well above said orifice; fluid inlet means communicating between said chamber and said pumping means; and valve means for permitting gas to escape from said chamber.

CLARENCE J. COBERLY.
